UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed March 13, 1924. Serial No. 699,123.

This invention relates to drilling mechanisms.

It has for its object to provide an improved drilling mechanism. A further object is to provide an improved feeding means for the drilling mechanism. Another object is to provide a drilling mechanism having steel rotation means, feeding means therefor and improved means responsive to the resistance to the rotation of said steel for controlling said feeding means. A further object is to provide improved means which is responsive to resistance to steel rotation for automatically controlling the feeding means for the drilling mechanism and which will have different degrees of responsiveness in accordance with different degrees of resistance to steel rotation. A further object is to provide an improved reverse and forward feed having improved means for controlling the same which is responsive to the resistance to rotation of the steel. It is another object to provide a drilling mechanism having reverse and forward feeding means, steel rotation means and a means responsive to variations in resistance to steel rotation for varying the forward feed, but when the steel becomes stuck to then reverse the feed.

In the accompanying drawings I have shown for purposes of illustration one form and a modification thereof which my invention may assume in practice.

In these drawings,—
Fig. 1 is a side elevation partly broken away to show details of construction.

Fig. 2 is a diagrammatic view of the improved feed control mechanism.

Fig. 3 is a modification of the feed control means.

Fig. 4 is a transverse vertical sectional view taken substantially on line 4—4 of Fig. 1. Fig. 5 is a detail sectional view of the valve 14 shown in Fig. 2, the valve being shown in a different position.

In the illustrative form of my invention I have shown the same embodied in a drifter type of drill comprising a combined feed cylinder and shell 1 having a depending bracket engaging member 2 and longitudinally disposed guideways 3 mounted on the upper side thereof. Slidably carried by the cylinder 1 is a drilling mechanism 4 having gibs 5 disposed within the guideways 3. Briefly the drilling mechanism comprises a

usual percussive motor cylinder 6 having a piston 7 of the striking bar type reciprocably mounted therein and adapted to hammer on a steel 8 carried by a chuck sleeve 9 rotatably mounted within a chuck housing 10 carried on the front end of the cylinder 6. Any suitable rotation mechanism may be used for actuating the chuck sleeve 9, but I have herein shown an independent rotation motor 11 of the multiple rotor type carried by the housing 10 and which is adapted to cooperate with worm gear teeth 12 formed on the periphery of the sleeve 9. Mounted within a rear cylinder head 13 is any suitable main control valve 14 having an automatic feed control valve 15 communicating with the main valve as by a passage 16.

The feeding means comprises an arm 17 carried by and projecting rearwardly from the lower side of the head 13 and terminating in downwardly projecting arms 18 which carry a conical bored member 19 at their lower end and within which is disposed a plug member 20. Threadedly connected to a reduced portion 21 of the member 20 is a hollow piston rod 22 projecting forwardly through a combined rear cylinder head and packing member 23, which rod 22 carries at its forward end a piston 24. Disposed within the forward portion of the piston rod 22 is a fluid conducting tube 25 projecting forwardly from a recess 26 formed in the plug member 20 and terminating in a head 27 fixed in the forward end of the rod 22.

In my improved device I have embodied means for automatically shutting down the feed when the drill steel suddenly encounters a hole or cavity, which ordinarily allows the feeding mechanism to jump forward and beyond the control of the operator. This means comprises a plug 28 held in the forward end of the hollow portion of the piston rod 22 as by a hollow nut 29 while formed therein is a bore 30 carrying a reciprocable spring pressed valve 31. As the hollow piston rod is used to conduct fluid for the forward feed, there is a passage 32, formed in the head 27 of plug 28, communicating with bore 30 which has communication with the rear end of piston 24 as by a longitudinal passage 33 and radial ports 34 formed in the valve 31, said ports communicating with a passage 35 leading to the rear side of the piston 24. A passage 37 is formed in the

piston 24 which allows communication between the forward end of the bore 30 and the rear side of said piston, the front side thereof having continuous communication 5 with the conducting tube 25 as by a passage 36.

In the operation of this automatic stop valve the piston 24 will in its normal operation be fed forwardly by a normal feeding 10 pressure within the cylinder 1, but when the steel encounters a hole and when the feed piston is in a position a substantial distance rearward from the position shown in Fig. 1, the feed piston will immediately jump forward, resulting in a reduced pressure within 15 the cylinder 1 which will reduce the pressure acting on the front side of the valve 31 through passage 37, thereby allowing the live pressure fluid within the hollow portion 20 of the piston rod 22 to force the valve 31 forwardly against the tension of its spring to shut off flow of fluid through the ports 34 and passage 35. If this closed condition is 25 maintained a sufficient length of time the actuating fluid within the cylinder 1 will regain normal pressure due to leakage from the ports 34 to the passage 35, and when such pressure is sufficient to feed the mechanism forward some more, if the same has a tendency to still jump, reduced pressure will 30 again result in the cylinder and the cycle of operation of the valve 31 will be repeated to shut off flow of fluid thereto. It will of course be understood that when the feed piston 35 is in the position shown in Fig. 1 and a cavity is encountered by the drill steel, the feed piston will move forwardly into engagement with the front cylinder head before the automatic control valve can come 40 into effect, the automatic control being operative to check the feed only when the feed piston is a substantial distance rearward from the position shown in Fig. 1.

My improved means for automatically 45 controlling the forward and reverse feed in accordance with tool rotation comprises the control valve 15 reciprocably mounted within a bore 40 and normally held in one end thereof as by a relatively weak spring 41 seated upon an adjusting screw 42 carried by 50 a plug 43 having threaded engagement with an enlarged bore 44 adjacent one end of the bore 40. Disposed within the bore 44 is a reciprocable collar 45 held in position by a relatively stiff spring 45'. The opposite 55 end of the bore 40 communicates as by a passage 46 with the inlet chamber 47 of the rotation motor 11. In the position of the valve 15 shown in Fig. 2, live pressure fluid 60 will flow from the main control valve 14 through passage 16, an annular groove 48 formed in the periphery of the valve 15 and passage 49 formed in the arm 17 leading to the hollow portion of the rod 22 which has 65 communication with the rear end of the cyl-

inder as previously described to thereby feed the same forwardly. If the rotors 11 should be slowed down due to increased resistance to rotation of the steel 8, the pressure of the fluid within the chamber 47 would be 70 increased and would thereby move the valve 15 against the tension of the relatively weak spring 41 to cause the passage 49 to be partially or wholly shut off from communication with the live fluid supply through passage 16, depending upon the amount of resistance to steel rotation. If, however, the resistance should become so great that the steel would stick and be entirely prevented from rotating or practically so, the pressure 75 in the chamber 47 would build up to substantially line pressure and thereby force the valve 15 up against the ring 45 with sufficient force to cause yielding of the relatively stiff spring 45', in which position the valve 15 will then vent the forward feed to atmosphere while allowing communication between the live pressure fluid supply controlled by the valve 14 and the reverse feeding passages to cause the drilling mechanism to be withdrawn until the steel again rotates. The passage means for accomplishing this reverse feed comprises a passage 50 leading from the port 56 in the valve 14 to the upper 80 end of the bore 40 which has communication with an annular groove 51 when said valve is in its outermost position to allow flow of fluid through the reverse passage 52 formed in the arm 17 and finally communicating with the front side of the piston 24 as by the tube 25 and passage 36 in the feed piston. During reversing position of the valve the forward feed is vented to the atmosphere through passage 35, port 34 and 85 passage 33 in the valve 31, passage 32, the hollow piston rod 22, passage 49, and a bypass 53 which will register with the groove 48 and vent passage 54 formed in the valve 14. When the forward feed is on, the reverse feed is vented to the atmosphere as 90 through passage 36, the tube 25, passage 52, a bypass 55, annular groove 51 and vent port 54 formed in the valve 14.

When it is desired to feed the mechanism in the reverse direction independently of the valve 15, the valve 14 is rotated until a port 56 registers with a passage 57 communicating with passage 52 on the other side of the valve 15. This new position of the valve 14 also shuts off live fluid flow to the passage 49 and consequently to the forward feed. A forward feed can always be obtained at the will of the operator by merely bringing the valve 14 into the position shown in Fig. 2 as the valve 15 will normally be retained in its lower position so as to have communication with the source of live pressure fluid.

It will thus be seen that by my improved automatic feed control valve the resistance to rotation of the steel can vary through a wide 130

range of limits and due to the relative weakness of the spring 41, the valve 15 will move in accordance with the varying degrees of resistance resulting in varying degrees of 5 forward feed, but never sufficient to throw in the reverse feed although it may at times be sufficient to entirely cut off the flow of fluid to the forward feed. If, after the forward feed has been cut off and the steel 10 is still rotating, the reverse feed is still vented to the atmosphere, but should the steel become positively held or the resistance to rotation become so great that the tool is practically inoperative, the spring 46 will 15 then be made to yield whereby the forward feed will be vented to the atmosphere and reverse feed thrown in. The operation during freeing of the steel will obviously be reversed.

20 In Fig. 3 I have shown a modified form wherein two separate valves are used in place of the single valve 15. This means comprises a primary valve 60 reciprocably mounted in a bore 61 and normally held at 25 one end of the bore as by a relatively weak spring 62. The valve 60 also has an annular groove 63 allowing communication between the passages 16 and 49 the latter communicating with the main supply and an 30 annular groove 64 adapted to allow communication between the passages 65 and 66 when the valve is in its uppermost position and to also vent the passage 66 as through a bypass 67 to the atmosphere, while the 35 groove 63 is adapted to vent the forward feed as by bypass 68 when the reverse feed is in. The passage 65, like the passage 50 in Fig. 2, communicates with the live pressure supply, in this case through the passage 57' which leads to the valve 14 while the passage 66 communicates with one end of a bore 69 within which a secondary valve 70 is normally yieldingly held at the lower 40 end of said bore 69 as by a relatively stiff spring 71 adjustably held as by a plug 72. The valve 70 has an annular groove 73 which in its lower position will vent the passage 52 and consequently the reverse feed as through a bypass 74 but while said valve is 45 in its uppermost position it will allow communication between the passages 50 and 52 leading from the throttle valve to the reverse feed.

50 In the operation of this modification, pressure variations in the rotation motor will be transmitted to the passage 45 and vary the position of the primary valve 60 to thereby vary the flow of fluid to the forward feed, or, if the resistance to steel rotation should 55 become too great to entirely shut off the flow of fluid to the forward feed and vent the same while at the same time allowing communication between the passages 65 and 66 as by the annular groove 64 which will thus 60 cause movement of the secondary valve 70

which will close the vent passage 74 and open communication between passages 50 and 52 leading from the main fluid supply valve 14 to the reverse feed to thereby withdraw the 70 steel and free the same.

In the operation of either form it is to be noted that during a "spotting" operation the sharp edges of the steel engaging the work causes a temporary sticking thereof but is 75 quickly released. This ordinarily causes jerking of the steel but by my improved sensitive feed control, the forward feed will be automatically turned off and on. However, the sticking is not of sufficient duration to throw in the reverse feed. The result is 80 that a very successful "spotting" operation may be had for the forward feed will always be automatically controlled but never allowed to fully recede from the face of the work.

85 While I have in this application specifically described one form and a modification thereof which my invention may assume in practice, it will be understood that these forms of the same are shown for purposes of illustration and that the invention may be modified and embodied in various other forms without departing from its spirit or the scope of the appended claims.

90 What I claim as new and desire to secure by Letters Patent is:

1. A drilling mechanism comprising a drilling motor, a steel actuated thereby, pressure fluid actuated rotation means for the steel, feeding means for the steel, and pressure fluid actuated means responsive to the resistance to rotation for automatically controlling said feeding means, said controlling means including means for providing therein sharply distinct degrees of responsiveness to said resistance and said controlling means comprising valve mechanism to vary the rate of feed up to a predetermined point and to cut out the feed when said point is exceeded.

100 2. A drilling mechanism comprising a drilling motor, a steel actuated thereby, pressure fluid actuated rotation means for the steel, feeding means for the steel, and pressure fluid actuated means responsive to the resistance to rotation for automatically controlling said feeding means, said controlling means including means for providing therein sharply distinct degrees of responsiveness and said controlling means comprising valve mechanism to vary the rate of feed up to a predetermined point and for further affecting said feed when said point is exceeded.

110 3. A drilling mechanism comprising a drilling motor, a steel actuated thereby, rotation means and reversible feeding means therefor comprising but a single reversible motor, and means responsive to a limited 120 resistance to rotation of said steel for vary- 130

ing the feed thereof, said means being responsive to a higher resistance to rotation of said steel to effect reversing of said feed.

4. A drilling mechanism comprising a drilling motor, a steel actuated thereby, rotation means therefor, reverse and forward feeding means therefor, and means responsive to the resistance to rotation of said steel for controlling said feeding means, said means including a plurality of sequentially operable members one of which allows variations of one feed while the other effects the other feed.

5. A drilling mechanism comprising a drilling motor, a steel actuated thereby, rotation means therefor, reverse and forward feeding means therefor, and means responsive to the resistance to rotation of said steel for controlling said feeding means, said means including a plurality of sequentially operable members one of which allows variations of one feed while the other member allows operation of the other feed after the first feed is shut off.

25 6. A drilling mechanism comprising a drilling motor, a drill steel actuated thereby, rotation means for the steel, feeding means for the steel, and means responsive to the resistance to steel rotation for controlling said feeding means, said controlling means including mechanism freely yieldable under resistance to steel rotation up to a certain degree and offering relatively marked increased resistance when said degree is exceeded.

7. A drilling mechanism comprising a drilling motor, a steel actuated thereby, rotation and pressure fluid actuated feeding means therefor, pressure fluid actuated means responsive to the resistance to rotation of said steel for automatically controlling the flow of fluid to said feeding means, and means for controlling said feeding means independently of the operation of said responsive means.

8. A drilling mechanism comprising a drilling motor, a steel actuated thereby, rotation and pressure fluid actuated feeding means therefor, pressure fluid actuated means responsive to the resistance to rotation of said steel for automatically controlling the flow of fluid to said feeding means, and means including a valve for controlling said feeding means independently of the latter means.

9. A drilling mechanism comprising a drilling motor, a steel actuated thereby, rotation and feeding means therefor, means responsive to the resistance to rotation of said steel for controlling said feeding means, and means including a by-pass passage for controlling said feeding means by cutting out operation of said latter means.

10. A drilling mechanism comprising a drilling motor, a steel actuated thereby, rotat-

tion and feeding means therefor, means responsive to the resistance to rotation of said steel for controlling said feeding means, and means for controlling said feeding means by cutting out operation of said latter means independently of said rotation means.

11. A drilling mechanism comprising a drilling motor, a steel actuated thereby, rotation means therefor, forward and reverse feeding means therefor, and means responsive to the resistance to steel rotation for automatically controlling both of said feeding means, said automatic controlling means being adapted to control said forward feeding means independently of the reverse feeding means when the steel is temporarily prevented from rotating during a "spotting" operation.

12. In a drilling mechanism, work performing means for actuating a tool comprising a reversible motor and a rotary motor, and means responsive to the torque of said rotary motor within a certain limit for varying the operation of the other motor, said means including mechanism responsive to reverse said latter motor when said limit is exceeded.

13. In a drilling mechanism, work performing means comprising a plurality of tool actuating motors one of which is reversible, and means responsive to load changes on one of said motors within a certain limit for varying the operation of another motor, said means including mechanism responsive to reverse said reversible motor when said limit is exceeded.

14. A drilling mechanism comprising a drilling motor, a drill steel actuated thereby, pressure fluid actuated rotating means for the steel, reversible feeding means for the steel, and pressure fluid actuated means responsive to the resistance to rotation for automatically controlling said feeding means, said controlling means including valve mechanism responsive to markedly different degrees of resistance to steel rotation to effect generically different controlling functions.

15. In a drilling mechanism, work performing means comprising a plurality of tool actuating motors, one of which is reversible, and means responsive to load changes within a certain limit on one of said motors for automatically controlling another, said means also being responsive to a greater load on said motor for automatically stopping and reversing said reversible motor.

16. In a drilling mechanism, work performing means for actuating a tool including a reversible motor, and pressure actuated means for automatically varying the power of said motor within a certain limit and to automatically reverse said motor when said limit is exceeded.

17. A drilling mechanism comprising a drilling motor, a drill steel actuated thereby, rotation means therefor, means for positively feeding the steel forwardly or rearwardly comprising but a single reversible motor, and means responsive to the resistance to rotation of said steel for automatically controlling both the rearward and forward feed including means for varying the forward feed automatically in accordance with the nature of the drilling encountered by the steel.
18. A drilling mechanism comprising a drilling motor, a drill steel actuated thereby, rotation means therefor, means for positively feeding the steel forwardly or rearwardly comprising but a single reversible motor, and means responsive to the resistance to rotation of said steel for automatically simultaneously affecting both the rearward and forward feeding means, and for varying the forward feed automatically in accordance with the nature of the drilling encountered by the steel.
19. A drilling mechanism comprising a drilling motor, a drill steel actuated thereby, rotation means therefor, means for positively feeding the steel forwardly or rearwardly comprising but a single reversible motor, and means responsive to the resistance to rotation of said steel within a certain limit for varying the forward feed and for subsequently stopping said forward feed when said limit is exceeded and effecting operation of said rearward feed.
20. A drilling mechanism comprising a drilling motor for actuating a drill steel, means for rotating the steel, means for positively feeding the steel forwardly or rearwardly comprising but a single reversible motor, and means responsive to the resistance to steel rotation up to a certain limit for varying the operation of the forward feed and when said limit is exceeded to automatically effect operation of said rearward feed.
21. A drilling mechanism comprising a drilling motor, a drill steel actuated thereby, rotation means therefor, reversible feeding means therefor comprising but a single reversible motor, and means responsive to the resistance to rotation of said steel for automatically varying the operation of said feeding means to regulate the same in accordance with the requirements of the work, said means including mechanism operative to automatically reverse said feeding means when the rotation of the drill steel is prevented.
22. In a drilling mechanism, a drill steel, pressure fluid actuated means for positively feeding the steel forwardly or rearwardly,
- and means responsive to the variations of pressure in said feeding means for automatically preventing an excessive rate of forward feed when the resistance to feeding movement encountered by said drill steel is substantially reduced.
23. In a drilling mechanism, a drill steel, pressure fluid actuated means for positively feeding the steel forwardly or rearwardly, and means comprising a pressure fluid actuated valve responsive to the variations of pressure in said feeding means for automatically preventing an excessive rate of forward feed when the resistance to feeding movement encountered by said drill steel is substantially reduced.
24. In a drilling mechanism, a drilling motor for actuating a drill steel, rotation means for the steel, reversible feeding means for the steel, means responsive to the resistance to rotation for automatically varying the power of or reversing said feeding means, and means for preventing an excessive rate of forward feed when the resistance on the drill steel is removed.
25. In a drilling mechanism, work performing means comprising a plurality of tool actuating motors one of which is reversible, and means responsive to load changes on one of said motors for automatically varying the power of said reversible motor during drilling in accordance with the requirements of the work or to reverse said reversible motor.
26. In a drilling mechanism, a fluid actuated motor, a tool actuated thereby, reversible feeding means for feeding the tool forwardly and rearwardly, and pressure fluid actuated valve means responsive to pressure conditions within said motor for automatically controlling the forward feed during drilling to vary the same in accordance with the requirements of the work, said means also being operative to reverse said feeding means when the pressure within said motor exceeds a predetermined point.
27. A drilling mechanism comprising a drilling motor, a drill steel actuated thereby, rotation means for the steel, feeding means for the steel for effecting positive forward and reverse feed thereof and comprising but a single reversible motor, and means responsive to resistance to rotation for automatically varying the rate of forward feed during drilling to vary the same in accordance with the requirements of the work, said controlling means also being operative to automatically reverse said feed when the resistance to rotation exceeds a predetermined point.

In testimony whereof I affix my signature.
CHARLES F. OSGOOD.
